UNITED STATES PATENT OFFICE.

NATHAN ROODMAN, OF NEW YORK, N. Y.

BRACELET.

1,309,657.

Specification of Letters Patent. Patented July 15, 1919.

Application filed November 9, 1918. Serial No. 261,810.

To all whom it may concern:

Be it known that I, NATHAN ROODMAN, a citizen of Russia, residing in the borough of Manhattan, in the city, county, and State 5 of New York, have invented certain new and useful Improvements in Bracelets, of which the following is a specification, reference being had therein to the accompanying drawings, which form a part thereof.

10 My invention relates to bracelets, and more particularly to a type thereof known as flexible block bracelets composed of a sequence of units pivotally connected in a manner to impart to the structure the desired flexibility to permit it to conform to 15 the forearm when being donned by the wearer.

Bracelets of the character to which my invention relates are ordinarily made in precious metal, such as gold or platinum, the 20 several units or blocks either being artistically finished as by chasing or engraving, or by having jewels mounted therein, or made up of both characters of blocks.

25 When working in precious metals, it is not only necessary to secure excellence in the workmanship and finish of such bracelets, but it is highly desirable to so construct and assemble the various blocks as to economize 30 the material entering thereinto, without sacrificing the strength of the structure to an extent which may result in the separation of the different blocks and a possible resulting loss of the bracelet.

35 With these conditions in mind, I have constructed a bracelet wherein all of the blocks excepting those at the ends carrying the catch mechanism, are of the same construction, these blocks being joined together in a 40 manner to secure the necessary degree of flexibility to permit the bracelet to assume an elliptical form. The structure of the hinge connection between adjoining blocks is such as to permit the convenient assembling 45 of each block and the rapid and convenient assembly of different blocks to form the completed structure. The different parts entering into each block are so constructed as to facilitate a permanent joinder of these 50 parts in a relation which will permit the proper fitting of the different blocks entering into the bracelet when assembling the same therein.

55 The invention consists primarily in a bracelet formed of a plurality of blocks each

composed of a channeled member, a hinge socket piece having a transversely extending opening therein, carried by, and projecting beyond the end of said channeled member, said channeled member having at the other 60 end of the side flanges thereof, openings adapted to register with the openings in the hinge socket piece of the adjoining member, and a hinge pin passing through the openings in said side flanges and through said 65 hinge socket piece, whereby said blocks are flexibly connected, and in such other novel features of construction and combination of parts, as are hereinafter set forth and described, and more particularly pointed out 70 in the claims hereto appended.

Referring to the drawings,

Figure 1 is a perspective view of a bracelet made in accordance with my invention;

Fig. 2 is an enlarged perspective view of 75 one form of block;

Fig. 3 is a view similar to Fig. 2 of another form of block; and

Fig. 4 is a perspective view of a modified 80 form of socket piece.

Like letters refer to like parts throughout the several views.

In the embodiment of my invention shown in the drawings, I have illustrated a flexible block bracelet formed of a plurality of 85 pivotally connected units, each comprising a block *a* of channeled material having substantially parallel ends, one end of said block having soldered, or otherwise secured therein, a hinge socket piece *b* having a 90 transversely extending elongated opening therein, the elongation of said opening being longitudinally of said block. This hinge socket piece in the form of the invention illustrated in Fig. 2, is formed of a flat- 95 tened metal tube of the same material as the block *a*, and includes therein a flattened portion *b'* adapted to seat upon the bottom of the channel in order to secure accuracy in the positioning of the piece, and to facilitate 100 the assembling of said piece in relation to said block. The flattened portion *b'* is preferably a small plate soldered to the tubular portion of the hinge piece.

Said hinge piece *b* and the flattened portion *b'* thereof, have a close fit with the side flanges of the block *a*, and the tubular portion thereof projects beyond the end of said block, so that in assembling a number of blocks in a completed bracelet, this projected 110

portion of the hinge piece b' will enter between the flanges of the adjoining block, and thus secure substantial continuity in the outer face of the bracelet. The side flanges 5 a' at the end thereof opposite the hinge piece b , have alined openings a^2 therein, adapted to register with the opening in the projected portion of the hinge piece b' of the adjoining block.

10 Adjoining blocks a are pivotally connected by means of hinge pins c having a close driving fit in the opening a^2 and a loose fit in the opening in the hinge piece b' . This loose fit between the hinge pin c and 15 the opening in the hinge socket piece, permits that slight relative movement of adjoining blocks necessary to permit the desired curvature of the completed bracelet in its entirety, the adjoining blocks separating slightly as the bracelet takes form, and the edges of the side flanges a' within the bracelet ultimately abutting so as to limit the amount of pivotal movement of said blocks. By this construction the degree of 20 flexibility of the bracelet is limited to that necessary to give it form while in use, the curved structure, when the ends are united, being substantially rigid, or sufficiently so to prevent the collapsing of the bracelet, or 25 its losing the elliptical form desired.

30 In the form of the invention shown in Fig. 3, the structure of the block a is as heretofore described, the sole difference being that the hinge piece instead of being formed of substantially elliptical tubular stock, is formed of a plate d having a close fit between the side flanges a' of the block a , and adapted to be soldered thereto, one edge of the plate d seating upon the bottom of the 35 channel of said block. Secured to the outer face of the plate d is a looped portion d' projecting beyond the end of the block a and forming a hinge socket adapted to receive the pin c of an adjoining block. This 40 form of the invention differs from that shown in Fig. 2 merely in the detailed construction of the hinge socket piece, and in that the amount of material entering into this form of a socket piece is slightly less 45 than that used in the form shown in Fig. 2.

50 In the form of the invention shown in Fig. 4, the construction is the same as that shown in Fig. 3, with the exception that instead of using a continuous loop such as d' , I employ two short loops $e-e'$, secured to a plate e^2 , similar to the plate d . The sole 55 advantage of the form of the invention shown in Fig. 4 is that the bulk of metal required in the hinge piece is reduced to a 60 minimum, without materially sacrificing the strength of the bracelet.

Where precious metals are employed, the saving of material is a matter of considerable importance, it being equally important, however, to secure sufficient strength

in the completed product to minimize the likelihood of breakage thereof under ordinary conditions of use.

The blocks a may be decorated in any desired manner, the form of the invention shown in Fig. 1 being such as to permit the setting of a brilliant in each block. The character of decoration, however, is a matter of individual taste, and, if desired, these openings may be dispensed with, and the decorative effect secured by chasing or engraving the entire outer surface of the blocks a .

By the construction herein described, so far as the structure of each block and its appurtenances are concerned, each block is a duplicate of every other, the construction being such that the various units entering into a bracelet may be assembled without any nicety in the fitting of parts; or in the adjustment of one unit in relation to the adjoining unit. If it be found that sufficient flexibility is not secured, this may be remedied by touching the ends of the block a with a file, to increase the quantity of movement of adjoining blocks with relation to each other, although ordinarily the play between the hinge pin c and the hinge socket piece b' , d' , or $e-e'$ is sufficient to permit that small separation of adjoining blocks, necessary to permit the desired small relative pivotal movement.

A bracelet made in accordance with my invention is assembled in the form of a straight strip of a length to secure the desired size, one end block thereof being provided with a keeper of the ordinary construction, coöoperating with a catch member carried by the other end block, such a catch being indicated at f in Fig. 1 of the accompanying drawings.

The various blocks, hinge socket pieces, and pivot pins, are preferably all made of the same metal, the ends of the pins c projecting beyond the side flanges a' , being cut off and the ends thereof finished in a manner to prevent any unsightliness resulting from the manner of assembling the various blocks. Of course the material of the various blocks is not material to the invention, although in practice the structure of my invention is ordinarily used only in bracelets formed of gold or platinum, or high grade articles.

The construction of each block is such that the hinge socket piece at one end thereof may be readily secured in place by being soldered to the channeled member, without likelihood of the solder entering the pivot opening in said hinge piece. Furthermore, the channeled member and the hinge piece may be readily handled when soldering.

In addition to a substantial saving of the material entering into each block, I am en-

abled, in a bracelet made in accordance with my invention, to produce each block with a substantial saving of labor, and yet retain in a completed bracelet, an intrinsic value measured by that of the precious metal embodied therein. In other words, a bracelet made in accordance with my invention, possesses all of the artistic and intrinsic values of flexible block bracelets wherein the structure of the blocks differs from that of the blocks embodied in my invention, and in addition thereto, such a bracelet possesses greater uniformity of structure throughout, can be more conveniently produced, and possesses the same, or greater, strength than other forms of bracelets of the same general character.

It is not my intention to limit the invention to the decorative characteristics of the bracelet, nor to other details of construction shown in the accompanying drawings, it being apparent that such may be varied without departing from the spirit and scope of the invention.

Having described the invention, what I claim as new and desire to have protected by Letters Patent, is:—

1. A bracelet formed of a plurality of blocks, each composed of a channeled member, a hinge socket piece having a transversely extending opening therein, carried by, and projecting beyond the end of, said channeled member, said channeled member having at the other end of the side flanges thereof, openings adapted to register with the opening in the hinge socket piece of the adjoining member, and a hinge pin passing through the openings in said side flanges and through said hinge socket piece, whereby said blocks are flexibly connected.

2. A bracelet formed of a plurality of blocks, each composed of a channeled member having substantially parallel ends, and a hinge socket piece having a transversely extending opening therein carried by, and projecting beyond the end of, said channeled member, said opening being elongated longitudinally of said member, the side flanges of said channeled member adjacent the other end thereof, having openings therethrough adapted to register with the opening in the hinge socket piece of the adjoining

member, and a hinge pin passing through the openings in said side flanges, and having a loose fit in the opening in the hinge socket piece of the adjoining block, whereby said blocks are flexibly connected.

3. A bracelet formed of a plurality of blocks, each composed of a channeled member, and a hinge socket piece carried thereby comprising a flat plate adapted to bear upon the bottom of said channeled member and having a close fit with the side flanges thereof, and a tubular portion carried by said plate, the opening of said tubular portion extending transversely of, and projecting beyond the end of, said channeled member, the side flanges of said channeled member adjacent the other end thereof having openings therethrough adapted to register with the opening in said tubular portion of said adjoining block, and a hinge pin passing through the openings in said side flanges and the tubular portion of an adjoining block, whereby said blocks are flexibly connected.

4. A bracelet formed of a plurality of blocks, each composed of a channeled member, and a hinge socket piece carried thereby comprising a flat plate adapted to bear upon the bottom of said channeled member and having a close fit with the side flanges thereof, and a tubular portion carried by said plate, the opening of said tubular portion extending transversely of, being elongated longitudinally of, and projecting beyond the end of, said channeled member, the side flanges of said channeled member adjacent the other end thereof having openings therethrough adapted to register with the opening in said tubular portion of said adjoining block, and a hinge pin passing through the openings in said side flanges, and having a loose fit in the opening in the hinge socket piece of the adjoining block, whereby said blocks are flexibly connected.

In witness whereof I have hereunto affixed my signature this 4th day of November, 1918, in the presence of two subscribing witnesses.

NATHAN ROODMAN.
